UNITED STATES PATENT OFFICE.

ROBERT ALEXANDER STURGEON, OF SOUTHSEA, ENGLAND.

CENTRIFUGAL MACHINE.

1,304,621.

Specification of Letters Patent. Patented May 27, 1919.

Application filed February 10, 1919. Serial No. 276,212.

To all whom it may concern:

Be it known that I, ROBERT ALEXANDER STURGEON, a subject of the King of England, and resident of Southsea, Hampshire, 5 England, have invented certain new and useful Improvements in Centrifugal Machines, of which the following is a specification.

This invention relates to centrifugal separating machines of the kind in which the 10 pressure produced in liquids due to centrifugal force is employed to produce relative axial movement between a piston and the cylinder in which it works. Hitherto such machines, although capable of treating 15 liquids containing little solid matter or mixtures of liquids of different specific gravities, have been primarily designed for dealing with liquids containing solid matter which it was desirable to discharge intermittently, without stopping the rotation of the 20 machine, in a more or less consolidated form. To this end such machines have hitherto been provided with a cover which was only opened after considerable relative 25 axial movement had taken place between the piston and cylinder.

A machine according to this invention is designed for the discharge of the heavier matter, whether solid or liquid, in a fluid or 30 semi-fluid state, so that it will flow freely from the machine instead of being ejected in the form of a cake. To this end, as soon as relative axial movement between the piston and the cylinder takes place, one end of 35 the cylinder is opened to allow the immediate escape from the cylinder of the heavier matter which the process of centrifuging has thrown against its walls.

In the preferred construction according to 40 this invention the machine comprises a cylinder having a fixed cover and a reduced opposite end, and a piston which carries a secondary piston or disk adapted to maintain closed the reduced end of the cylinder during 45 the centrifuging of the liquid under treatment. The relative axial movement between the piston and cylinder, whereby the reduced end of the latter is closed, is effected by the pressure produced in the liquid by 50 centrifugal force, and axial movement in the opposite direction immediately causes the opening of the reduced end of the cylinder and thus permits of the discharge of the heavier matter. This reverse axial movement is preferably effected by the pressure 55 set up by centrifugal force in a liquid admitted to the opposite surface of the piston.

Figure 1 is a vertical cross section through the centrifugal machine;

Figs. 2, 3, 4, 5 and 6 are similar cross 60 sections showing the parts in different positions.

A is the cylinder provided with a fixed cover A' and mounted upon a hollow spindle 65 B. C is a piston having a baffle plate C' and carrying a cover plate C². The cylinder A is formed with a reduced open end at A² and the plate C² is adapted to form a joint with the end A² of the cylinder. The parts B, C, C', and C² are all adapted to rotate together in ball bearings.

The spindle B has an inlet passage B' through which the liquid to be treated is admitted to the cylinder, and an inlet pipe D is provided to admit water into the space between the cover A' and the piston C.

The operation is as follows:

While the machine is stationary the parts occupy the relative positions shown in Fig. 1, but upon starting the machine and admitting—through the inlet B'—the liquid to be treated the latter is thrown out against the inner face of the cylinder and forms an annular ring of liquid the inside diameter of which is determined by the diameter of 85 the reduced open end A² of the cylinder (Fig. 2). The pressure of this liquid ring is sufficient to force the piston C upward until the cover plate C² closes the open end A² of the cylinder (Fig. 3), the clarified liquid 90 being allowed to escape through holes C³ near the center of the plate C². When it is considered that a sufficient quantity of the heavier portion has been separated the flow of the liquid is stopped and another 95 liquid is admitted—through the inlet D—to the upper side of the piston (Fig. 4) and the pressure produced by the centrifugal force set up in this liquid compels the piston C to slide downward, breaking the joint between the plate C² and A² and ejecting the contents of the cylinder (Figs. 4 and 5); into suitable receptacles, not shown; after 100 which the inlet D is closed and a further supply of the liquid to be treated is admitted through the inlet B'. Fig. 6 shows the position of the parts after the inlet D has been closed and a small amount of liquid to be clarified admitted to the cylinder, the piston being on its return or upward journey.

The liquid by which the piston is caused to move downward escapes through an outlet or leakhole A³ which is so proportioned relatively to D that it does not allow the

said liquid to escape as quickly as it is admitted.

It is obvious that this process may be used as a means for concentrating liquids in which case the clarification of the lighter liquid becomes the secondary purpose. In no case, however, is it desired to obtain solids in such a degree of concentration that they will not flow readily through the troughs and conduits into which they are discharged.

It is also clear that this construction of the machine may be varied by a suitable rearrangement of the parts, or by the use of a separate cylinder or piston for operating the main centrifugalizing cylinder.

What I claim as my invention and desire to secure by Letters Patent is:—

1. In a centrifugal machine the combination with a separating cylinder of a piston within the cylinder and adapted to be actuated by the pressure produced by centrifugal force in the liquid being treated and means moving with the said piston for closing the outlet from the cylinder by which the solids or heavier liquids are discharged.

2. In a centrifugal machine, the combination of a cylinder mounted for rotation and having suitable apertures for the entrance and discharge into and out of the opposite ends thereof of two liquids, one of which is the liquid to be centrifuged, a piston within the cylinder separating the said liquids and adapted to be actuated by the pressures produced by centrifugal force in said liquids, and means moving with the piston at all times for closing the outlet from the cylinder by which the solids or heavier liquids are discharged.

3. In a centrifugal machine, the combination of a cylinder mounted for rotation and having an opening in one end for the discharge of centrifugal products and suitable additional apertures therein for the introduction of a liquid to be centrifuged and for the introduction and discharge of other liquid, a piston in said cylinder separating said liquids and adapted to be actuated by differences in pressures of said liquids on opposite sides thereof produced by centrifugal force, and means attached to the piston for closing the opening through which the solids or heavier liquids are discharged.

4. In a centrifugal machine, the combination of a cylinder mounted for rotation and having a circular opening in one end of slightly less diameter than the inner diameter of the cylinder for the discharge of centrifugal products and having a suitable aperture for the introduction of liquids to be centrifuged, a reciprocable piston in said cylinder and a disk connected to said piston and adapted to close the circular opening

of said cylinder when in one position and to immediately open the said opening to allow the solids or heavier liquids to be discharged when the piston is moved toward said opening.

5. In a centrifugal machine, the combination of a cylinder mounted for rotation and having a circular opening in one end of slightly less diameter than the inner diameter of the cylinder, for the discharge of centrifuged products having a suitable aperture for the introduction at any time of a liquid to be centrifuged, a reciprocable piston in said cylinder, and a disk rigidly connected to said piston and adapted to close the opening in said cylinder when the piston is at one end of its stroke, said disk having a small central opening through which clarified liquid may continually flow from said cylinder and said circular opening being immediately opened for the discharge of solids and heavier liquids when the piston is moved.

6. In a centrifugal machine, the combination of a cylinder mounted for rotation and having a circular opening in one end of slightly less diameter than the inner diameter of the cylinder for the discharge of centrifuged products, a hollow shaft having an aperture, for introducing liquid to be centrifuged, a reciprocable piston in said cylinder, and a disk in spaced relation to said piston and rigidly attached thereto, said disk being adapted to close the circular opening in said cylinder when the piston is at one end of its stroke, said disk having a small central opening through which the clarified liquid may continually flow from the cylinder, the circular opening being immediately opened for the discharge of solids and heavier liquids when the piston is moved.

7. In a centrifugal machine, the combination of a cylinder mounted for rotation, and having suitable openings for the introduction and discharge of two different liquids, one of which is the liquid to be centrifuged, a piston in said cylinder adapted to separate said liquids at all times and to be actuated when there is an unbalanced force acting on one side due to differences in pressures in the two fluids, produced by centrifugal action, a valve controlling the discharge of solids and heavier liquids thrown against the wall of said cylinder by centrifugal force and a connection between the valve and the piston whereby the valve is held closed when the piston is at one end of its stroke, and is immediately opened when it is moved from this position.

In testimony whereof I have signed my name to this specification.

ROBERT ALEXANDER STURGEON.
